Primary Examiner — Ricky Pham(74) *Attorney, Agent, or Firm* — Sturm & Fix LLP(57) **CLAIM**

The ornamental design for a pot, as shown and described.

DESCRIPTION

FIG. 1 is a perspective view of the upper part of the pot with a lid attached thereto, showing my new design;
FIG. 2 is a top view of the upper part of the pot;
FIG. 3 is a front elevational view of the upper part of the pot, the opposite side being a mirror image of the side shown;
FIG. 4 is a bottom view of the upper part of the pot;
FIG. 5 is an exploded view of the various parts of the claimed design, including the upper and a lower part of the pot;
FIG. 6 is a perspective view of the lower part of the pot;
FIG. 7 is a top view of the lower part of the pot;
FIG. 8 is a front elevational view of the lower part of the pot; and,
FIG. 9 is a bottom view of the lower part of the pot.
The broken lines shown in the drawings are for illustrative purposes only and form no part of the claimed design.
